CLAIM

The ornamental design for a plastic container, as shown and described.

DESCRIPTION

FIG. 1 is a front, top perspective view of a plastic container showing our new design.

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom view thereof.

The elements depicted in broken line segments of equal length form no part of the claimed design.
